UNITED STATES PATENT OFFICE

2,031,732

ANDIRON

Francis J. Plym, Niles, Mich., assignor to The Kawneer Company, Niles, Mich., a corporation of Michigan

Application December 10, 1934, Serial No. 756,789

3 Claims. (Cl. 126—298)

The present invention relates to andirons and more in particular to a novel construction thereof provided with means for positively retaining a fire screen or other protective device.

5 Among the objects of the present invention is the provision of a novel andiron construction for fireplaces and the like.

A further object of the invention is the provision of an andiron construction provided with 10 novel means of retaining a fireplace screen or guard in position. By reason of the present construction, complete protection is afforded since it eliminates all danger of collapse or tipping over of the screen as so frequently happens with 15 the present forms of screens which are generally made of folded sections or a single screen and are unstable and easily tipped over.

Another object of the present invention is the provision of an andiron construction in which 20 the logs may be more easily handled and completely consumed.

Further objects are to provide a construction of maximum simplicity, efficiency, economy and ease of assembly and operation, and such further objects, advantages and capabilities as will 25 later more fully appear and are inherently possessed thereby.

In the drawing:

Fig. 1 is a view in perspective of a fireplace with 30 the novel andirons in position.

Fig. 2 is a view in vertical cross section taken in a plane represented by the line 2—2 of Fig. 1.

Fig. 3 is a view in perspective of an alternate construction.

35 Fig. 4 is a view in perspective of another form in which the andirons are made separate.

Referring more particularly to Figs. 1 and 2 of the drawings, the novel andiron construction 1 is shown in position in a fireplace A. The construction comprises inclined side members 2 for receiving logs or the like B. These side members 2 seat at their rear end upon the base or floor of the fireplace and are each provided at 40 their front end with a reverse bend forming a substantially U-shaped portion or leg 3 connected by means of a cross bar 4. These U-shaped portions provide a recess or depression 5 in which the lower end of a screen or other protecting device 6 is adapted to be seated and retained against accidental displacement. This feature is of extreme importance as a safety measure, both in 45 protecting the room against burning embers, and also in preventing a child or adult from accidentally knocking over the screen. Also this screen

may cover the entire opening of the fireplace and thereby afford a complete protection.

By reason of the inclination of the side members, the logs or the like B always move toward the rear of the fireplace and due to their position 5 on an inclined surface, are always assured of sufficient draft for proper combustion.

Fig. 3 discloses an alternate form of andiron construction 1^a in which the side members 7, although inclined toward the rear, are also convex. The forward end of each side member is provided with a U-shaped sustaining portion or leg 8 providing a recess or depression 9 for a screen or other protective device, and an extension 10 providing an additional leg for adding 15 stability to the structure. The inner or rear ends of the side members 7 are connected by a cross bar 11.

A further alternate construction is shown in Fig. 4 in which the side members 12 form separate 20 andirons. These members or andirons are likewise inclined rearwardly but are also concave. Each member is provided at its forward end with a downwardly extending part 13 providing a base 25 14 and an outwardly and laterally extending leg or face piece 15. Between the part 13 and the laterally extending leg 15 is formed a recess or groove 16 for the reception and retention of a screen or other protection for a fireplace.

From the above description and the disclosure 30 in the drawing, it will be readily apparent that the invention comprehends a novel construction of andirons having inclined sides, which at their forward ends are provided with a recess or groove 35 for receiving and retaining a screen or like construction in fixed position without danger of accidental displacement and affording complete protection.

The andirons may be shaped in various forms 40 and provided with numerous designs or ornamentation, as desired. Also they may be made separate or with a connecting bar, and also may be concave or convex, in addition to their inclination.

Having thus disclosed the invention,

I claim:

1. An andiron comprising a continuous bar having a downwardly and rearwardly sloping fuel supporting portion and a forward leg portion formed with a reverse bend providing an elongated upwardly opening recess for reception and retention of a protecting screen.

2. In an andiron construction, a pair of andirons each comprising a continuous bar having a downwardly and rearwardly sloping fuel sup-

45

50

55

porting portion and a forward leg portion formed with a reverse bend providing an upwardly opening recess for reception and retention of a protecting screen, and a cross member connecting said andirons.

5. An andiron construction for receiving logs and the like in a fireplace in combination with a protecting screen therefor, said construction com-

prising a pair of andirons each consisting of a continuous bar having a downwardly and rearwardly sloping fuel supporting portion and a forward leg portion formed with a reverse bend providing an upwardly opening recess for the 5 reception and retention of the protecting screen.
